(57) **CLAIM**

The ornamental design for an auger handle bar, as shown and described.

DESCRIPTION

FIG. 1 is an isometric view of an auger handle bar showing the new design;

FIG. 2 is a front elevation view thereof, the back elevation view thereof being a mirror image of the front elevation view; FIG. 3 is a left elevation view thereof, the right elevation view thereof being a mirror image of the left elevation view thereof;

FIG. 4 is a top plan view thereof;

FIG. 5 is a bottom plan view thereof; and,

FIG. 6 is another left elevation view of the auger handle bar of FIGS. 1-5 illustrating environment.

The broken lines in FIGS. 1-6 are for illustrative purposes only and form no part of the claimed design.
